(57) **CLAIM**

The ornamental design for a fiber optic splitter module with surface ornamentation, as shown and described.

DESCRIPTION

FIG. 1 is a front perspective view of a fiber optic splitter module with surface ornamentation showing our new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is another front perspective view thereof.

The even-broken lines in the drawings are included for the purpose of illustrating unclaimed environmental structure and form no part of the claimed design. The dash-dot broken lines represent the boundary of the claimed design. In FIGS. 1, 2 and 8, the lighter stippling indicates a contrast in texture, where the heavier stippling may have a different texture than the lighter stippling, or may have the same texture as the lighter stippling.

1 Claim, 6 Drawing Sheets
